UNITED STATES PATENT OFFICE.

THOMAS HARDING, OF NEWARK, NEW JERSEY, ASSIGNEE TO J. L. SOMMER MANUFACTURING CO., A CORPORATION OF NEW JERSEY.

CORKSCREW.

Application filed February 20, 1926. Serial No. 89,629.

This invention relates to a combined bottle cap remover and corkscrew of the type which include a body of sheet metal one end of which is shaped to form crown cap removing jaws and upon which is pivotally mounted at one end a corkscrew which is adapted normally to lie along one edge of the body in an out-of-the-way position and to serve as a gripping surface for operation of the bottle cap remover.

One object of the present invention is to provide a device of this character including novel and improved means for covering the point of the corkscrew when the latter is in inoperative position and for holding the corkscrew against accidental pivotal movement from its inoperative position.

Other objects are to provide a novel and improved manner of pivotally connecting the corkscrew to the body of the device whereby the corkscrew may be held in its inoperative position by frictional engagement of the corkscrew with the body; to provide such a device which shall be simple and inexpensive in construction, and to obtain other results and advantages as may be brought out by the following description.

Referring to the accompanying drawings, in which corresponding and like parts are designated throughout the several views by the same reference characters,

Figure 1 is a side elevation of a combined bottle opener and corkscrew embodying the invention;

Figure 2 is an elevation of the lower edge of the device;

Figure 3 is an elevation of the side thereof opposite that shown in Figure 1;

Figure 4 is an enlarged transverse vertical sectional view, taken on the line 4—4 of Figure 3, with the corkscrew bit shown in operative position, and

Figure 5 is a horizontal sectional view, taken on the line 5—5 of Figure 3, with the corkscrew bit shown in operative position.

Specifically describing the illustrated embodiment of the invention, the reference character 1 designates the body of the device which is preferably formed of one piece of flat sheet metal, one end of which is shaped to provide bottle cap removing jaws 2 of known construction. Intermediate its ends, one edge of the body 1 is offset as at 3 from the plane of the body to provide a pivot recess to receive a pivot eye 4 on a

corkscrew 5, the corkscrew being pivotally connected to the body by a headed pivot pin 6 passing through the eye 4 and the opening 7 substantially co-axial with the offset portion 3. Between the offset portion 3 and the end of the body opposite the jaws 2, the edge of the body is cut away as at 8 to receive the bit of the corkscrew. Obviously, the corkscrew may be swung about the pivot pin 6 into the position at substantially right angles to the body 1, as shown by dot and dash lines in Figure 1, or alongside the body 1 in the cut away portion 8, as shown by solid lines in Figure 1.

To protect the point 10 of the corkscrew against contacting with exterior objects or from injuring the hand of the user, the body is provided with a notch 11 one edge 12 of which is arranged eccentric to the pivot pin 6 so that when the corkscrew is swung into inoperative position the point 10 will enter the notch 11 and frictionally bear against the eccentric edge 12, as shown in Figures 2 and 3, so that the point 10 is enclosed, and through the frictional engagement of the point with the edge of the notch the corkscrew is held against accidental pivotal movement out of the cut away portion 8. It will be noted that the inherent resiliency of the corkscrew will provide a yielding engagement of the point 10 with the eccentric edge 12 of the notch 11.

To further ensure against the corkscrew becoming accidentally swung out of the cut away portion 8, the base of the offset portion 3 may be formed in a plane oblique to the axis of the pivot pin 6, as indicated at 13, and the side of the pivot eye 4 engaging the base of the offset portion may be similarly formed in a plane at an angle to the axis of the pivot pin, as at 14. The oblique surfaces 13 and 14 are so disposed that when the corkscrew is in its operative position at right angles to the body 1, the surfaces 13 and 14 are parallel or coincide, while when the corkscrew is swung toward the cut away portion 8, the surface 14 frictionally binds upon the surface 13 due to the movement of the surface 14 into a position at an angle to the surface 13, and this frictional engagement serves to hold the corkscrew in inoperative position. Also the oblique or cam surfaces 13 and 14 serve as frictional stops to hold the corkscrew bit against movement in one direction out of operative position, 110

while the side wall of the recess at 15 provides a stop for movement of the corkscrew bit in the opposite direction. Obviously, cam projections or cooperating projections and recesses on the offset portion and on the pivot eye would operate similarly to the surfaces 13 and 14.

A device constructed as above described is simple and inexpensive, and the means for holding the corkscrew in inoperative position are reliable in operation and will compensate for slight inaccuracies in manufacture and wear incident to use. The advantages of holding the corkscrew bit in closed position by cam surfaces or means arranged at its eye are that there is no tendency to bend or distort the corkscrew bit, but both it and its sharp point are left entirely free so that there is also no tendency to blunt or dull the latter.

While I have shown the corkscrew combined with a bottle opener, it is within the scope of the invention to combine the corkscrew with another article or to mount the corkscrew upon a plain handle in the manner described.

Having thus described the invention, what I claim is:

1. A corkscrew comprising a body, a corkscrew bit pivotally connected at one end to said body upon an axis transverse to said body to swing alongside of and away from the body, said body having a surface parallel to said axis transversely of the plane of swinging of the bit and eccentric to said axis in said plane of swinging of the bit which surface is engaged by the side of the pointed end of the bit as said bit is swung alongside of the body to frictionally hold said bit in closed position.
2. A corkscrew comprising a body, a corkscrew bit pivotally connected at one end to

said body upon an axis transverse to said body to swing alongside of and away from the body, said body having a notch transverse to the plane of swinging of said bit to receive the pointed end thereof and said notch having one side wall parallel to said axis transversely of the plane of swinging of the bit and eccentric to said axis in said plane of swinging, said side wall being frictionally engaged by the side of said pointed end of the bit as the bit is swung alongside of said body and said pointed end of the bit shielded in said notch and the bit frictionally held closed alongside the body.

3. A corkscrew comprising a body having an opening, a corkscrew bit having a pivot eye surrounding said opening and lying laterally against the body, the contacting surfaces of said body and pivot eye having cam projections which coincide when the corkscrew bit is in closed position and are spaced circumferentially when said bit is in open position.

4. A corkscrew comprising a body having an opening in a portion of its surface which is oblique to the axis of said opening, a corkscrew bit having a pivot eye formed with a surface oblique to the axis of said eye and engaging said surface on said body, and a headed pivot member passing through said eye and said opening in the body to pivotally connect said bit to said body so that the former may be disposed alongside of and at an angle to said body, said oblique surfaces frictionally engaging each other when the bit is swung into a position alongside of said body to hold the bit in such position and also serving as frictional stops to restrain movement of said bit into said position.
